Atty.

UNITED STATES PATENT OFFICE.

JAMES KENNEDY McCOMB, OF TORONTO, ONTARIO, CANADA.

GARMENT.

1,367,666.

Specification of Letters Patent.

Patented Feb. 8, 1921.

Application filed January 12, 1920. Serial No. 351,048.

To all whom it may concern:

Be it known that I, JAMES KENNEDY McCOMB, a British subject, residing in the city of Toronto, in the county of York and Province of Ontario, Dominion of Canada, have invented certain new and useful Improvements in Garments; and I hereby declare that the following is a full, clear, and exact description of the same.

10 This invention relates to an improvement in a housedress, wrapper, or the like, and the object of the invention is to so make the garment that it may be quickly adjusted to neatly fit the figure of persons of different 15 bust, waist and arm measurements, this object being attained as hereinafter set forth and particularly pointed out in the claims.

In the drawings:

Figure 1, is a fragmentary perspective 20 view of a garment turned inside out and worn by a relatively stout woman,

Fig. 2, is a similar view to Fig. 1, showing the same garment worn by a woman of smaller dimensions, and

25 Fig. 3, is a fragmentary detail view showing in plan the material cut for the sleeve and part of the bust.

Like characters of reference refer to like parts throughout the specification and 30 drawings.

Heretofore in this class of garment it has been necessary for a merchant to carry in stock an assortment of sizes to meet the requirements of the trade with regard to the 35 variations of the bust, waist, and arm measurements of his customers, and often at the end of the season he has a large portion of the stock on hand on account of there being no demand for certain of the sizes. This entails an unnecessary investment of capital 40 and a consequent increase in the price of the garment to the purchaser.

In carrying out the present invention I find that it is only necessary to make two 45 sizes of garment, one for large bust measurements and the other for medium bust measurements. In both cases I form the sleeve a and bust a' with a gore b , which extends from the wrist band a'' of the sleeve 50 to the waist band b' of the bust, and provide this gore with three sets of spaced eyelets c , d and e , the eyelets c being secured to the gore in the vicinity of the elbow, the eyelets d being secured to the gore at the shoulder, 55 and the eyelets e being secured to the gore at

the waist line. Each set of eyelets c , d and e is preferably secured to a strip of fabric material c' , d' , and e' respectively, these strips being arranged transversely to the length of the gore and sewn along their 60 edges to the gore material to form pockets for the draw strings f , g and h inserted through the eyelets c , d and e respectively, and by means of which the eyelets of each set can be pulled together and tied in their 65 contracted position.

The wrist band a'' may be provided with a set of fasteners a^3 by which it may be regulated to snugly embrace the wrist, so that when the draw string f is pulled 70 through the eyelets c , they, in conjunction with the wrist band, will regulate the size of the sleeve between the elbow and the wrist band. Likewise, the draw string g and eyelets d in conjunction with the draw 75 string f and eyelets c , will regulate the size of the sleeve between the elbow and the shoulder and will also regulate the upper part of the bust to the body, and the draw string h and eyelets e will regulate the size 80 of the lower part of the bust and the waist.

By the use of the gores, the eyelets, and draw strings, a garment made for the largest size of person within its range can be contracted to neatly fit the figure of the 85 smallest person within its range. Thus a garment having a 42" bust can be adjusted by means of the draw strings, eyelets and gores to neatly fit any figure between a 42" and a 34" bust, the material of the sleeve, 90 bust and waist being drawn to the figure by the manipulation of the draw strings. In this way it is only necessary for a merchant to carry two sizes of garments in stock, and the wearer, without any alteration of the garment, can adjust it quickly 95 to neatly fit the figure, and thus always present a well-dressed appearance. While I have shown and described one convenient and practical means of regulating the size 100 of the sleeve and bust, I wish it to be understood that other means within the scope of the claims may be substituted for them.

Having thus fully described my invention, what I claim as new and desire to secure by Letters Patent is:

1. In a garment comprising a bust, sleeve, and a gore inserted in the garment extending from the waist line of the bust to the wrist band of the sleeve, the combination of 110

means for regulating the size of the sleeve and means for regulating the size of the bust.

2. In a garment comprising a bust, a sleeve, and a gore inserted in the garment and extending from the waist line of the bust to the wrist band of the sleeve, the combination of means secured to the garment at the sides of the gore in the vicinity of the 5 elbow for regulating the size of the sleeve between the elbow and wrist band, means secured to the garment at the sides of the gore in the vicinity of the shoulder for regulating the size of the sleeve between the 10 elbow and shoulder and for regulating the size of the upper part of the bust, and means secured to the garment at the sides of the gore in the vicinity of the waist band for regulating the size of the lower part of the 15 bust and waist band.

3. In a garment comprising a bust, a sleeve, and a gore inserted in the garment and extending from the waist line of the bust to the wrist band of the sleeve, the 20

combination of means secured to the garment at the sides of the gore in the vicinity of the elbow for regulating the size of the sleeve between the elbow and wrist band, means secured to the garment at the sides of the gore in the vicinity of the shoulder for 25 regulating the size of the sleeve between the elbow and shoulder and for regulating the size of the upper part of the bust, and means secured to the garment at the sides of the gore in the vicinity of the waist band for 30 regulating the size of the lower part of the bust and the waist band, said means comprising three sets of eyelets mounted in strips of fabric material and provided with draw strings, each set of eyelets and its respective string being secured to the garment at appropriate position for the regulation of 35 the size of the sleeve and the bust.

Toronto, Ontario, January 10th, 1920.

JAMES KENNEDY McCOMB.
